COOLING RECEPTACLE

William T. Marsh, Woodmere, N.Y., assignor to Fuller Displays, Inc., Long Island City, N.Y., a corporation of New York

Filed Apr. 24, 1956, Ser. No. 580,370

1 Claim. (Cl. 206—44)

My invention relates to an improved receptacle for exhibiting articles of merchandise, and particularly a receptacle adopted to protect such articles from the effects of heat and warmth when put on sale in shops and market places.

An important object is to provide an open receptacle in which articles of merchandise can be disposed and subjected constantly to the action of a cooling agent in the receptacle to such an extent that all risk of spoiling and deterioration because of unsuitably high temperature in the surroundings, is obviated.

Another object is to provide a cooling or refrigerating container that is simple in construction, requiring no special cooling apparatus, and quite certain and efficient in operation.

The drawings illustrate preferred forms of the invention, and the nature and advantages are fully set forth herein. But I do not wish to be limited to the exact embodiment actually shown, for changes in numerous minor respects may be adopted without departure from the general design as defined in the appended claim.

On the drawings:

Figure 1 is a plan view of a blank sheet material, such as cardboard, shaped and scored so that it can be easily manipulated and set up to complete the receptacle.

Figure 2 is a perspective view of the receptacle as it appears when finished.

Figure 3 shows the body of the receptacle with all parts connected, but collapsed for storing or shipping.

Figure 4 is a plan view of a modified form of blank.

Figure 5 is a sectional view of a detail.

Figure 6 is a perspective view of the receptacle formed with the blank shown in Figure 4; and

Figure 7 is a perspective view of the rear portion of the receptacle of Figure 6 with portions attached to the rear in readiness to be bent into final position.

The receptacle as presented in Figures 1, 2, 3 and 4 is preferably made of corrugated cardboard, the outer faces of which have been treated to render them entirely waterproof, and the blank is so shaped that there are no openings in it at any low point. The portion 1 for the bottom of the box is quadrangular and located at the middle of the blank and the side and end portions are also quadrangular. The transverse score lines 2 and 3 are parallel, and mark the portions 5 and 6 for the ends of the receptacle, but the line 2 is longer, and the bottom portion 1 thus tapers from the line 2 to the line 3. The longitudinal score lines 4 define the edges of the bottom portion between the ends, and these lines converge at equal angles from the ends of the line 2 towards the line 3. The end portions 5 and 6 are rectangular and hinge-connected to the bottom along the transverse score lines 2 and 3 respectively; and along the outer terminal edges the end portions 5 and 6 have flaps 7 and 8 hinged to the respective end portions along transverse lines similar to the lines 2 and 3.

The portions 9 for the sides of the receptacle are alike in size and configuration and hinge-connected to

2

the portion 1 along the score lines 4. The portions 10 connecting the side and end portions are joined to the side portions 9 along score lines 11, marking the transverse terminal edges of the side portions, adjacent the lines 2 and 3 respectively; and to the end portions 5 and 6 along the score lines 12, which are joined to the ends of the lines 4. The portions 10 are flaps connecting the side and end portions. They have the general form of an L and each has a diagonal score line 13 running from 10 the re-entrant corner 14 to the junction of the lines 11 and 12 at the extremities of the lines 2 and 3, dividing each flap into two adjacent sections.

The side portions 9 each have a diagonal score line 15 running from the adjacent extremity of the line 2, 15 at the common junction of the side, adjacent end and bottom portions, and a diagonal score line 16 running from the adjacent extremity of the line 3 at a similar junction. These lines 15 and 16 meet at adjacent points 20 on the outer edges of the portions 9, and divide said portions into three contiguous sections; one 17, extending fully along the adjacent line 4 and two triangular sections 19, one connected to each adjacent flap 10 and both to the adjacent section 17.

The score lines 11 are not straight continuations of the lines 2 and 3, but make such an angle therewith, and the sections of each flap 10 are of such shape and relative location, and the inclination of each score line 13 is such that, when the flaps 10 are folded along the line 13, the two sections of each flap coincide. This 30 position is assumed when the end portions 5 and 6 and the side portions 9 are bent up perpendicular to the bottom portion 1 and the sections of the flaps 10 are securely stapled to themselves and the end portions 2 and 3, or so secured by other means. The receptacle then has 35 the appearance portrayed in Figure 2.

The score lines above mentioned enables the box to be collapsed by folding the portions 5 and 6 down on the bottom portion 1. The sides are then folded along the lines 15 and 16 to lay the sections 19 of the sides 40 down on the section 17, the latter being turned outward as indicated in Figure 3. The collapsed receptacle then has the appearance of a polygon with two sides 4a parallel and two pairs of converging sides 15a and 16a, or six long sides in all. Thus flattened the box can be 45 stored or shipped in a small space, and can be set up at once by pulling upward on the edges of the portions 5 and 6. This action unfolds the sections of the side portions 9.

The flaps 7 and 8 on the portions 5 and 6, when the 50 receptacle is finished, are turned down and secured over the folded flaps 10. See Figure 2. They then may serve as handles for lifting the receptacle. One of the flaps 7 on the portion 5 is wider and is bent along three transverse score lines 20, so that the portions between the 55 score lines 20 can be folded and project inward and form a flange. Such portions have registering perforations making a hole 21 to receive a rod or staff 22, bearing a display card 23. To hold the rod steady, a tab 25 is cut in the portion 5 and a hole 26 is formed 60 in the tab. When the tab is bent inward the holes 21 and 26 are in alignment and the rod is engaged at two separated points. The flange may be at the upper edge of the portion 6 or a little above said edge.

The receptacle being moisture-proof because the outer 65 layers of the cardboard are treated as required, is well adapted to receive, and hold small containers with contents that must not be allowed to become warm, such as milk and other food products. A cake of ice or other refrigerant can be placed in the receptacle and the merchandise piled into the receptacle upon and around the ice, or a cooling agent in a suitable enclosing package can be utilized. If ice is selected, the melting will re-

sult in some water, but the water will be retained in the receptacle because it is leak-proof at all points and cannot run out on the shelves or floor.

The receptacle shown in Figures 5, 6 and 7 is also shaped from water-proof cardboard, and the bottom portion 1 has the same outline as before. But the end portions 5 and 6 are not quite rectangular and are respectively wider adjacent the flaps 7 and 8 than along the parallel lines 2 and 3.

The portions 10a and 10b connecting the side portions to the respective end portions 5 and 6, are respectively joined to the side portions 9 along transverse score lines 11a and 11b at the ends of the lines 2 and 3 respectively, and to the end portions 5 and 6 along the longitudinal score lines 12a and 12b, respectively, which are united to the ends of the lines 4. The portions 10a and 10b again are flaps having the general form of an L, and again each has a diagonal score line 13 running from the re-entrant corner 14 to the junction of the side and adjacent end portions at the extremities of the lines 2 and 3. But the sides 9 have no diagonal scores 15 and 16 previously mentioned.

The score lines 12a and 12b between the flaps 10a and 10b and the respective end portions 5 and 6 are not parallel, but diverge respectively from the lines 2 and 3. Hence the transverse score-lines 27 and 28 along the connected edges of the flaps 7 and 8 are longer, respectively, than the lines 2 and 3, and each of the end portions 5 and 6 has an outline which tapers toward the portion 1. Further, the score-lines 11a and 11b again are not straight continuations of the lines 2 and 3, but makes such an angle therewith, and the sections of each flap 10a and 10b are of such shape and relative location, and the inclination of each score line is such that, when these flaps are folded along the lines 13, the two sections of each flap coincide. This position is assumed in Figure 6 when the end portions 5 and 6 and the side portions 9 are bent up not perpendicular to the bottom portion 1 and the folded sections of the flap 10a and 10b are securely stapled to themselves and the end portions 5 and 6, or so secured by other means. The portions 9 are wider along the score lines 12a, and with the other portions having the configuration above set forth, the box has an open top larger than the bottom 1, and tapers from the end portion 5 towards the end portion 6. Also the top edge of the receptacle is lower along the end portion 6, and the upper edges of the side portions slope from the end portion 5 to the end portion 6, which is intended to be the front of the recep-

tacle. The box shown in Figure 6 also has the perforated flange and tab 25 for the rod 22.

The receptacle of Figures 5, 6 and 7 being narrower and of less height at its front end, and the area of the open top being greater than the bottom, has a shape that permits a number to be assembled in nesting relation, for convenience in shipping and storing. For nesting purposes the flaps 8 are not folded, but allowed to remain flat and projecting. See Figure 7. When any receptacle is needed for use, the tab 25 is bent inward and the flap 7 is folded as shown in Figure 2. When the rod is in place, the flap and tab and rod are all held securely in the positions required.

Having described my invention, what I believe to be new is:

A moisture-proof receptacle having a bottom, sides and ends, one end being higher than the other, said sides and ends having sloping top edges between said ends, inside folded flaps in pairs; one of each pair being united to one side and the adjacent end and being hinge-connected to each other along a diagonal score line, and fully uniting the sides and ends; said folded flaps of each pair overlying each other at each junction of an end and side; the higher end having a relatively long flap hinged thereto along its upper edge; said flap having three transverse score lines thereon defining with said upper edge four transverse portions on said flap, the portion nearest said upper edge and the outermost portion being superposed inward of said receptacle, the other two portions being superposed and bent to project over the bottom, said other two portions having aligned openings to receive a staff bearing a display card for said receptacle; said higher end having, projecting from its inner face, a tab with one opening in line with the aforesaid openings.
